M. J. WALTHER

HEATER FOR GAS AND OIL STOVES

Filed Feb. 13, 1926

UNITED STATES PATENT OFFICE.

MATHIAS J. WALTHER, OF LAKEWOOD, OHIO.

HEATER FOR GAS AND OIL STOVES.

Application filed February 13, 1926. Serial No. 88,056.

This invention relates to heaters for gas and oil stoves and has for an important object thereof the provision of a device of this character which may simultaneously be placed over a plurality of burners and which will concentrate the heat from these burners to heat a plate upon which cooking vessels may be placed.

A further object of the invention is to provide a device of this character which may be very readily and cheaply produced, which will be durable and efficient in service and a general improvement in the art.

These and other objects I attain by the construction shown in the accompanying drawing, wherein for the purpose of illustration is shown a preferred embodiment of my invention and wherein:—

Figure 1 is a perspective view of a warmer constructed in accordance with my invention;

Figure 2 is a plan view thereof;

Figure 3 is a section on the line 3—3 of Figure 2;

Figure 4 is a section on the line 4—4 of Figure 2;

Figure 5 is a section on the line 5—5 of Figure 1;

Figure 6 is an enlarged section taken through the connection between the flanges to show the manner of attaching the plates together.

Referring now more particularly to the drawings, the numeral 10 generally designates a plate having at its side edges downwardly and outwardly extending flanges 11 which are joined at their adjacent edges by suitable folded seams 12. Beneath the plate 10 is arranged a second plate 13 disposed in spaced relation to the plate 10 and having openings 14 formed therein. This plate 13 has at its side edges flanges 15 similar to the flanges 11 of the plate 10 and adapted to fit against the interior faces of the lower ends of these flanges. The lower ends of the flanges 15 are reverted upon the outer faces of the lower ends of the flanges 11, as at 16,

and the flanges 11 and 15 are secured against relative displacement by punchings or some corresponding expedient, as indicated at 17. It will be obvious that a plate of this character may be very readily and cheaply produced and may be very lightly constructed.

In the use of the device, the openings 14 are placed over two burners in event it is desired to cook materials placed, in suitable utensils, upon the upper surface of the plate 10. If it is merely desired that these materials be warm, a single burner is ordinarily sufficient.

It will be obvious that the construction hereinbefore set forth is capable of a certain range of change and modification without materially departing from the spirit of the invention and I accordingly do not limit myself to such specific structure except as hereinafter claimed.

I claim:—

A heater for gas and oil stoves comprising a sheet metal plate having at its side edges downwardly and outwardly inclining flanges, said flanges being connected at adjacent ends thereof by folded seams, a second plate of slightly greater size than the first named plate arranged below the first named plate and extending between the lower ends of the flanges thereof, said second named plate having flanges similar to the flanges of the first named plate, the lower edges of the flanges of the last named plate being reverted against the outer faces of the flanges of the first named plate whereby the flanges of the last named plate have portions abutting the inner and outer flanges of the portions of the flanges of the last named plate to provide a seam, the metal at the seam being displaced transversely of the seam to thereby prevent relative displacement of the first and last named plates, the last named plate having openings for alignment with the burners of a stove.

In testimony whereof I hereunto affix my signature.

MATHIAS J. WALTHER.
